FOUR-IN-HAND TIE

Filed June 23, 1927

Inventor
Merr W. Reese
George E. Mueller Atty.

UNITED STATES PATENT OFFICE

MERL W. REESE, OF OMAHA, NEBRASKA.

FOUR-IN-HAND TIE

Application filed June 23, 1927. Serial No. 200,843.

My invention relates to men's neck-wear. It has to do more specifically with an improved type of four-in-hand tie having a very pleasing appearance when tied.

5 An objectionable feature in connection with previously known four-in-hand ties, is the fact that when they are tied about the collar, the knot will pull the silk in unevenly, and it is difficult to outflare the body portion of the tie beneath the knot so that the tie will hang straight. Not only will the body portion of the tie appear crooked but the knot is very apt to twist sideways and either one of these conditions will make an otherwise presentable 10 tie have an unsightly appearance. The care required in tying a four-in-hand tie to make it hang straight and the unsatisfactory results so often obtained in spite of such care can be attested by many who have had this 15 experience.

The object of the present invention is the production of an improved type of four-in-hand tie.

Another object is the production of a four-in-hand tie which is more easily tied about the collar than ties heretofore known.

Another object is to produce a tie having a more pleasing appearance when around the collar.

30 Another object is to produce a tie which will hang straight and evenly when around the collar.

Another object is to produce a tie wherein the body portion is easily outflared below the 35 knot piece.

The tie is featured by a narrow portion designed to be included within the knot piece so that no major portion thereof extends outwardly from either the upper or lower end 40 thereof. The body of the tie extends outwardly from the knot at the point in which the narrowed portion expands to normal size. The narrowed portion is formed by arcuate excisions on the two sides of the usual straight 45 edges of the body portion in a manner which will be described.

Other objects and features of the invention may become apparent from a consideration of the detailed description taken with the 50 accompanying drawings, wherein—

Fig. 1 is a perspective view showing the appearance of my improved four-in-hand tie when knotted;

Fig. 2 is a fragmentary plan view showing the arrangement of the body portion of the 55 tie;

Fig. 3 is a sectional view along the line 3—3 of Fig. 2, and

Fig. 4 is a fragmentary view of the tie in process of construction.

My invention is illustrated as applied to a so-called tailored four-in-hand tie, that is a tie produced by cutting a pattern from a body of material and sewing the pattern together to produce the tie structure.

Without making specific reference to the manner in which the tie is produced, it comprises a main body portion 10 with a neck portion 11 and an intermediate portion 12 adapted to be knotted to form a knot piece 13 as illustrated in Fig. 1. Between the intermediate portion and body portion, is formed a pair of oppositely disposed arcuate cut-away portions 14 and 15 which as the tie is knotted, are included in the knot in the manner illustrated. This portion is below the knot as indicated in the drawing. The two cut-away portions result in a narrowed section which decreases the amount of lateral contraction of the edges or sides of the tie 70 below the knot and thus reduces or prevents wrinkling of the tapered body portion 10, adjacent the knot. As a result the body portion of the tie is more easily outflared just below the knot to have a symmetrical appearance which is obtained with difficulty, if at all, if the tie is of the full width at this point.

The arrangement will be more easily understood from a consideration of one manner in which the tie may be made. The 90 pattern is cut flat with the same general outline as to produce any good tailored tie. At the proper position near the edges 16 of the blank, however, two leaf-shaped excisions 17 are cut, these excisions being produced in 95 any suitable way. The tie is actually made of two blanks sewed in the center at the neck, to form a continuous strip, but this is not of prime interest here, and has not been shown.

When the blank is produced, the edges 17a 100

of each leaf-shaped opening are sewed together flat, and the edges 16 of the tie are also sewed so that a tubular body is formed with the edges 16 and 17a on the outside. After this the tubular body is reversed or turned "inside out" so that the edges 16 and 17a are inside of the tubular body and concealed from view. The usual filler 18 is introduced into the tubular body in any suitable manner to increase the body and stiffness of the tie where necessary. It is of course provided with side incisions to correspond with the narrowed portions in the body of the tie. Afterwards the tie is flattened out and a neck piece 19 is sewed onto the neck portion of the tie in the position shown in Fig. 1. The stitchings 21 for the neck piece are along the edge of the neck portion of the tie and may serve to anchor the filler 18 in place. At the lower portion of the body of the tie however, a cross stitch 22 is provided to reinforce the open edge which is left at the lower part of the body and this cross stitch may also be sewed to the filler. After the tie is fully completed, it is of course pressed in the usual manner so that the edges will lie flat throughout the length of the tie.

The foregoing description referring to the manufacturing of the tie holds true only when a so-called tailored tie is made. Even with this class of tie however, the method may be modified and the stitching be employed in an entirely different manner. In a full knitted tie, the arcuate "cut-away" portions might be knitted right into the tie, or they might be produced in a manner shown and described for a tailored tie. The method of making a tie is not of prime importance as long as the effect that I have outlined is produced. For this reason I do not limit myself to any particular construction except as pointed out in the appended claims.

What I claim as new and desire to secure by United States Letters Patent is:

1. The method of forming a four-in-hand tie which comprises cutting a pattern of great length in relation to its width, with a pair of openings whose sides are shaped as intersecting arcs, stitching the longitudinal edges of the pattern together to form a tube, sewing the opposed edges of the openings together, reversing the tube, and pressing it flat so that the sewed openings form arcuate portions at the side edges of the completed tie.

2. In a four in hand tie a tube formed of silk and pressed flat having a lining with the general outline of the flat body, the tie including a neck portion with an extension at one end adapted for extending under the knot piece, a knot tying portion at the other end of the neck portion and a body portion connected with the knot portion and adapted to hang below the knot piece when the knot tying portion is formed into a four in hand

knot, the portion between the knot portion and body portion being narrowed by two arcuate excisions at the sides, the edges of the tie being turned inwardly and the tie stitched to hold the arcuate edges together, and the lining also being cut away in the region of the arcuate excisions.

In witness whereof, I hereunto subscribe my name this 19 day of May, 1927.

MERL W. REESE.
